[57] ABSTRACT

Anionic detergent compositions for shampoos and household use are provided of which the essential components are a synergistic combination of an iodate and an amine. The iodate is preferably sodium, potassium or ammonium iodate up to an amount of 5 percent and the detergent is preferably sodium, potassium, ammonium or an alkanolamine sulphated fatty alcohol, a secondary alkyl sulphate or a salt of ethoxylated sulphated alcohol having 1 to 3 ethylene oxide units per mole. The compositions have antimicrobial properties and are virtually self-sterilizing. The metal iodate preferably constitutes 0.25 to 0.5 percent of the composition which in addition to the anionic detergent includes an inert, innocuous carrier adjuvant such as a coloring agent or perfume. The anionic detergent is a non-soap, non-sulphonate compound and its synergistic action with the metal iodate is unrelated to the liberation of iodine.

5 Claims, No Drawings

DETERGENT AND SHAMPOO COMPOSITIONS

This application is a continuation-in-part of my application Ser. No. 493,884 filed Oct. 7, 1965 now abandoned.

The present invention relates to anionic detergent compositions, and in particular to shampoo compositions.

It is known that on storage anionic detergent compositions are subject to microbial spoilage, and in shampoos this can be particularly troublesome, and may result in precipitation, discoloration, gas formation and offensive odors. Antimicrobial agents have therefore been included in anionic detergent compositions, but difficulties are encountered in ensuring compatibility with the constituents of the composition.

It is an object of the present invention to provide anionic detergent compositions especially for but not limited to shampoos in which the above disadvantages are avoided.

Accordingly the present invention provides an anionic detergent composition comprising an anionic, non-soap, non-sulphonate detergent and less than 5 percent of a preservative and synergistic metal iodate unrelated to the liberation of iodine, together with at least one other material serving as an innocuous or inactive adjuvant.

Preferably the metal iodate is sodium, potassium or ammonium iodate, at a concentration of about 0.5 to 0.1 percent w/v (e.g., as $\text{NaIO}_3 \cdot \text{H}_2\text{O}$).

It has been found that, while sodium, potassium and ammonium iodates in aqueous solution have little antimicrobial activity, in the presence of an anionic detergent there is high antimicrobial activity that is retained on prolonged storage of the composition. Additionally, these iodates have been found to be compatible with anionic detergents and the compounds are colorless and odorless.

The following non-limitative examples illustrate the invention.

EXAMPLE 1

The synergistic effect of detergent and iodate against spoilage organisms was shown by comparing the spoilage rates of solutions of mixed lauryl sulphates with and without added sodium iodate with those of distilled water and of sodium iodate solution.

10 **Materials****Detergent:**

Ammonium lauryl sulphate, 4 parts

Monoethanolamine lauryl sulphate, 1 part

Triethanolamine lauryl sulphate, 1 part

15 **Solutions were diluted to Cetavlon Value 245.**

Sodium Jodate: $\text{NaIO}_3 \cdot \text{H}_2\text{O}$. Solutions at 0.1% w/v concentration.

Spoilage Organisms

A number of micro-organisms were isolated from spoiled shampoo and detergent solutions; they consisted of *Pseudomonas*, *Klebsiella*, and *Citrobacter* types, together with various unclassified Gram-negative rods. Subcultures were grown in nutrient broth for 24 hours at 37°C. Single loop transfers were made to 9 ml. aliquots of nutrient broth and further incubated for 24 hours. The broth cultures were pooled, and 0.25 ml. of this suspension was inoculated into each test solution.

20 **Method**

Duplicate 25 ml. aliquots of sterilized test solutions were distributed in sterile MacCartney bottles, each bottle containing 30 glass balls. After inoculation with organisms, which were thoroughly dispersed with a Vortex JR mixer, the mixtures were incubated at room temperature. Plate counts in nutrient agar were carried out at intervals over the following four weeks.

The results are shown in Table I.

TABLE I

Test Solution	Colony count :							days after inoculation
	0 (3 hrs)	1	2	7	14	21	28	
Detergent	795	9,000	0.3×10^6	2.5×10^6	10^6	0.5×10^6	1.3×10^6	
Detergent + iodate	110	<10	<10	<10	<10	<10	<10	
Iodate	10^6	10^6	10×10^6	61×10^6	68×10^6	85×10^6	50×10^6	
Distilled Water	10^6	10^6	10×10^6	100×10^6	155×10^6	183×10^6	105×10^6	

Suitable anionic detergents include sodium, potassium, magnesium and ammonium or organic base, such as ethanolamine or other lower alkanolamine of one to four carbon atoms, derivatives of sulphated fatty alcohols, secondary alkyl sulphates and salts of ethoxylated sulphated fatty alcohols having 1 to 3 ethylene oxide units per mole. A particularly desirable anionic detergent is a mixture of ammonium lauryl sulphate with mono- or triethanolamine sulphate, or both.

Adjuvants included in the compositions are of the usual type, such as coloring agents, perfumes, cream bases for certain types of shampoos, and for liquid household detergent compositions, i.e., innocuous and inert.

55 It can be seen that only the solution of detergent plus iodate has remained free from bacterial contamination. Neither component individually is able to check growth of organisms to any marked degree. Similar experimental work in which the sodium iodate was replaced by

60 potassium and ammonium iodates showed their efficacy at the same concentration of 0.1 percent w/v in preventing bacterial contamination. When sodium iodate was used at concentrations up to 0.5 percent, bacterial contamination was again prevented.

EXAMPLE 2

Preservation of liquid shampoo with sodium iodate.

TABLE III

Formulation	%
(1) Triethanolamine lauryl sulphate ("36% active")	45.00
Formaldehyde solution (38-40% w/v)	0.05
Perfume	0.50
Dye Solution	5.00
Water	to 100.00
(2) As above with addition of 0.1% w/v sodium iodate	(NaIO ₃ ·H ₂ O).

Method

Samples (100 ml.) of each of the above formulations were inoculated 14 days after manufacture with 1.5×10^6 spoilage organisms; a second pair of samples were inoculated 28 days after manufacture with 2×10^6 organisms. Broth sterility tests were performed and bacterial counts estimated at weekly intervals.

The results are shown in Table II.

TABLE II

Inoculation: days after manufacture	Sterility test: days after inoculation	Organisms per ml.	
		Formulation 1	Formulation 2
14	14	1,500	<10
	28	100,000	<10
28	14	180,000	<10
	28	1,000,000	<10

It can be seen that sodium iodate causes effective sterilization of the shampoo, and that it is stable to storage, whereas when the shampoo composition contained formaldehyde alone as preservative, bacterial contamination occurred.

EXAMPLE 3

Preservation of cream shampoo with sodium iodate.

Formulation	%
(1) Ammonium lauryl sulphate	66.7
Monoethanolamine lauryl sulphate }	3.5
Ethylene glycol monostearate	0.5
Lauric isopropanolamide	0.2
Anhydrous lanolin	0.006
Dye	0.5
Perfume	0.0625
10% sodium hydroxide solution	to 100
Water	
(2) As (1), with phenylmercuric borate	0.005
Formalin	0.05
(3) As (1), with sodium iodate NaIO ₃ ·H ₂ O	0.1

Method

Samples (200 g.) of each of the above formulations were inoculated 10 days after manufacture with spoilage organisms to give a concentration of 5×10^6 organisms/g. Plate counts were carried out over the following three weeks.

The results are shown in Table III.

Formulation	Colony count: days after inoculation		
	6	20	20
1	750,000	300,000	300,000
2	50,000	80,000	80,000
3	40	<10	<10

Shampoo containing iodate became effectively sterile; shampoo preserved with phenylmercuric borate and formalin was only marginally better than the unpreserved formulation.

EXAMPLE 4

Preservation of liquid cream shampoo with iodate

Formulation	% w/v
(1) Sodium lauryl ether sulphate	55.6
Empilan CDE*	2.8
Ethylene glycol monostearate	2.5

Water	to 100.0
(2) As (1) with 0.05% w/v Formalin	
(3) As (1) with 0.25% w/v Sodium iodate	
(4) As (1) with 0.5% w/v Sodium iodate	
(5) As (1) with 0.5% w/v Ammonium iodate	

* diethanolamine fatty acid amides (foam stabilizer)

TABLE IV

Formulation	Colony count:	days after inoculation
1.	7	14
2.	>10 ⁶	>10 ⁶
3.	700,000	>10 ⁶
4.	1,000	6,000
5.	<10	33,000
		1,300
		7,000
	11,000	3,150
		<10

Microbiological findings indicated that the unpreserved formulation was highly susceptible to bacterial spoilage. It was found that sodium iodate (0.1 percent) prevented the development of the native microbial flora initially in the unpreserved shampoo. However, it can be seen that the incorporation of 0.25 - 0.5 per cent iodate drastically reduced the spoilage rate in experimentally infected shampoos and is superior to 0.05 percent formalin.

EXAMPLE 5

Preservation of liquid cream shampoo with ammonium, potassium and sodium iodates

Formulation	% w/v
(1) Monoethanolamine lauryl sulphate	50
Ammonium lauryl sulphate	
Ethylene glycol monostearate	2.5
Empilan AL*	0.7
Anhydrous lanolin	0.14
Perfume	0.5
Polypeptides	1.0
Dye	0.006
(2) As (1) with 0.1% w/v ammonium iodate	
(3) As (1) with 0.1% w/v potassium iodate	
(4) As (1) with 0.1% w/v sodium iodate	

* diethanolamine fatty acid amides (foam stabilizer)

TABLE VI

Formulation % iodate	A			B			C			
	14	28	56	Colony count:	14	28	days after inoculation	14	28	56
1. Nil	>10 ⁵	>10 ⁵	>10 ⁵	>10 ⁵	>10 ⁵	>10 ⁵	>10 ⁵	>10 ⁵	>10 ⁵	>10 ⁵
2. 0.05	500	11,000	1,300	7,200	<100	6,000	46,000	1,000	15,000	
3. 0.1	<10	<10	<10	1,380	20,000	1,300	<10	<10	<10	<10
4. 0.25	<10	2,500	<10	<10	<10	<10	<10	<10	<10	<10
5. 0.5	<10	<10	<10	<10	<10	<10	<10	<10	<10	<10

Method

Sets of five tubes each containing a 10 ml sample of shampoo were inoculated 14 days after manufacture with graded numbers of shampoo spoilage organisms to give a microbial population varying from 10⁶ to 100 organisms in each tube. After storage at local ambient temperature for 14 days, the shampoos were examined for evidence of microbial contamination by means of broth and agar sterility tests.

TABLE V

Numbers of tubes of shampoo demonstrating viable organisms 14 days after experimental inoculation					
Experimental inoculum. orgs/ml.	Shampoo preserved with 0.1%			Unpreserved	
	Ammonium iodate	Potassium iodate	Sodium iodate	Control shampoo	
10 ⁶	0/5	0/5	0/5	3/3	
10 ⁵	0/5	0/5	0/5	4/4	
10 ⁴	0/5	0/5	0/5	4/4	
10 ³	0/5	0/5	0/5	4/4	
10 ²	0/4	0/5	0/5	4/4	

Shampoo containing either ammonium, potassium or sodium iodate became effectively sterile, whereas shampoo without these preservatives demonstrated microbial contamination.

EXAMPLE 6

Formulation

- (1) As in Example 5. (1).
(2) As (1) with 0.05% w/v iodate:

A=Ammonium iodate,
B=Potassium iodate,
C=Sodium iodate.
A, B and C as in (2)
A, B and C as in (2)
A, B and C as in (2)

- (3) As (1) with 0.1% w/v iodate;
(4) As (1) with 0.25% w/v iodate;
(5) As (1) with 0.5% w/v iodate:

Ammonium, potassium and sodium iodate had each effectively prevented the development of microbial spoilage organisms in experimentally infected shampoos. When an iodate was used at concentrations up to 0.5 percent, the product became resistant to microbial attack and was virtually self-sterilizing to spoilage organisms.

What is claimed is:

- 20 1. An anionic detergent composition for shampoo and household use consisting essentially of a synergistic combination of
a. triethanolamine lauryl sulphate, monoethanolamine lauryl sulphate or ammonium lauryl sulphate or a mixture thereof, and
b. 0.1 to 5 percent w/v of a metal iodate selected from the group consisting of sodium iodate, potassium iodate and ammonium iodate as active ingredients.
- 25 30 2. An antimicrobial composition the essential active components of which are a synergistic combination of (1) sodium, potassium or ammonium iodate in an amount of 0.1 to 0.5 percent w/v and (2) triethanolamine, monoethanolamine or ammonium lauryl sulphate or a mixture of such lauryl sulphates.
- 35 3. An anionic detergent composition for shampoo and household use consisting essentially of synergistic combination of
a. ammonium lauryl sulphate, monoethanolamine lauryl sulphate and triethanolamine lauryl sulphate in combination with
b. 0.1 to 5 percent sodium iodate.
- 40 4. An anionic detergent composition for shampoo and household use consisting essentially of a synergistic combination of
a. triethanolamine lauryl sulphate in combination with
b. 0.1 to 5 percent w/v sodium iodate.
- 45 5. An anionic detergent composition for shampoo and household use consisting essentially of a synergistic combination of
a. ammonium lauryl sulphate and monoethanolamine lauryl sulphate in combination with
b. 0.1 to 5 percent w/v sodium iodate.

* * * * *

Method

Shampoos were inoculated with spoilage organisms 14 days after manufacture to give 8 × 10⁶ organism/ml. The results are shown in Table VI.
